[57] CLAIM

The ornamental design for a housing for a security console, as shown and described.

DESCRIPTION

FIG. 1 is a front perspective view front of a housing for a security console showing my new design, with the undisclosed rear being plain and unornamented;

FIG. 2 is a perspective view looking from the bottom and opposite side thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof.

FIG. 1.

FIG. 2.

FIG. 3.

FIG. 4.

FIG. 5.

FIG. 6.

FIG. 7.
